TUBULAR KNITTING MACHINE

Raymond H. Carhart, East Syracuse, N. Y., assignor to W. C. Lipe, Inc., Syracuse, N. Y., a corporation of New York

Application January 24, 1938, Serial No. 186,592

7 Claims. (Cl. 66—79)

This invention relates to tubular fabric knitting machines of the type referred to in my Patent No. 2,091,467 issued August 31, 1937, and has for its object means for preventing the cloth from becoming entangled in the land-and-cast-off or double burr or for relieving this burr from abnormal strains, that it would otherwise be subjected to, due to roughness in the cloth, as knots, holes, and other similar conditions, and hence preventing upsetting, distorting or disarranging of the burr wheel and damage to the cloth.

The invention consists in the novel features and in the combinations and constructions hereinafter set forth and claimed.

In describing this invention, reference is had to the accompanying drawings, in which like characters designate corresponding parts in all the views.

Figure 1 is a fragmentary plan, partly in section, of a portion of a tubular knitting machine showing the inside burr wheel with means for relieving it of strains of the cloth, the contiguous parts or burr wheels of the knitting mechanism and their relation to the needle ring being also shown.

Figure 2 is a sectional view on line 2—2, Figure 1.

Figure 3 is an enlarged face view of the land-and-cast-off burr and its support.

Figure 4 is a sectional view on line 4—4, Figure 3.

Figure 5 is a rear elevation on a reduced scale of parts seen in Figure 3.

Figures 6 and 7 are views similar to Figures 3 and 5 of another exemplification of the invention.

A tubular fabric knitting machine of this class comprises, generally, a suitable bed or frame, a rotating needle ring or cylinder, a rotating cloth frame including mechanism for winding up the cloth, as it is knitted, knitting mechanism carried by the bed and stationary with respect to the rotation of the needle ring, and suitable actuating mechanism for the needle ring and for winding the cloth.

As this type of machine is old and well known, it is thought that description thereof is unnecessary.

1 designates the rotating needle ring or support for the needles 2. The ring 1 is provided with suitable spokes 3 which are supported on a central shaft, not shown. The ring 1 is in effect a turn-table supported by the frame or bed of the machine. The cloth is carried in the same manner as in any knitting machine of this type and takes a generally tubular form, and the finished cloth wound is in a roll by the usual mechanism.

The knitting mechanism includes a clearing burr wheel 4, a sinker burr wheel 5, and a land, castoff or double burr wheel 6, and a cloth presser or wheel 7. The burr wheels 4 and 5 and the

cloth wheel 7 are called "outside" knitting elements, which are mounted on suitable supports, not shown, on an outer stationary ring 8 forming a part of the frame or bed of the machine, and there are a plurality of sets of such mechanism arranged side by side around the outside ring 8. The burr wheels 6 are oftentimes referred to as the "inside" burrs, they being located on the inner side of the needle ring and there is one of such burr wheels in each set of knitting mechanism.

This invention comprises means adjacent the inside burr wheel, that is, the land-and-cast off burr for coaxing with the knitted cloth to relieve the double burr of abnormal strains which would otherwise be transmitted thereto, due to roughness and imperfections in the cloth, as knots, etc., which abnormal strains tend to distort, damage or disarrange the double burr wheel 6. This means comprises an arcuate shield around the rear portion of the periphery of the burr wheel, with respect to the direction of rotation of the needle ring, it extending from a point near the needle ring around or part way around the burr wheel and being so located that the cloth is fended off from the burr wheel at a point near the needle ring, and hence prevented from following the burr wheel around, when the cloth becomes entangled in the burr wheel, as when a hole in the cloth catches on the blades of the burr wheel. It will be understood that the cloth is being pulled upwardly over a feed roll as it is knitted and is also rotating with the needle ring. Hence, if the portion of the cloth at the burr wheel should become entangled in the blades of the burr wheel, the pull of the cloth will be against the shield and the strains borne by the shield and not by the burr wheel and also the cloth can not follow around the burr wheel.

In Figures 1, 2, 3, 4 and 5, the shield 11 is shown as a cup enclosing the rear side, with respect to the direction of rotation of the needle ring, and the periphery of the wheel 6, the shield having a cut-out 12 at its margin adjacent the needle ring or adjacent the needles of the ring in mesh with or coaxing with the burr wheel. The burr wheel is nested in the shield or cup. The shield is carried by a shank 13 by means of which the burr wheel is supported from a suitable bracket on the bed of the machine, as shown in my patent referred to. The shield or cup 11 is formed with an axial recess 14 in its bottom and a stud 15 is arranged axially of the recess, and the burr wheel is formed with a hub having an axial opening for receiving the stud. The shield is normally arranged at an inclined angle or plane with the open side of the shield or cup facing upward, so that the burr wheel is merely placed over the stud, and no provision is required for preventing it from coming off the stud, especially as the movement

of the needle ring normally tends to hold the burr wheel in the cup and on the stud. The burr wheel, as here shown, includes a body 16 having a hub 17 having a bushing 18 therein, the bushing extending through the body 16. A retaining nut 19 is threaded on the stud against the body 16.

In Figures 6 and 7, the shield 11^a instead of being a cup is located on the rear edge only of the burr wheel, with respect to the direction of rotation, and extends from a point near the needle ring and the cloth approximately a quarter way around the periphery or bladed edge of the burr wheel, and is supported by a radially extending arm 11^b from a hub 11^c which is formed with a recess and bearing stud 15 for the burr wheel.

The needle ring rotates in the direction of the arrow (Figure 1) and in case the cloth, due to holes in the cloth, knots or other abnormal conditions, becomes entangled or tends to become entangled in the burr wheel, the shield 11 or 11^a prevents the cloth from following around the burr wheel and bending the blades or the teeth of the burr wheel, and also relieves the burr wheel of the pull of the cloth, due to the cloth traveling with the rotating needle ring, and otherwise protects the burr wheel and relieves it of strains that it would otherwise be subjected to under abnormal conditions tending to upset, damage or disarrange the burr wheel.

30   What I claim is:—

1. In a tubular fabric knitting machine including a suitable bed, a rotating needle ring, and sets of knitting mechanism carried by the bed and stationary with respect to rotation of the needle ring, each set including a burr wheel located on the inner side of the needle ring with a portion of its periphery coacting with the needle ring and cloth adjacent the ring; of means adjacent said burr wheel for coacting with the cloth to relieve the burr wheel of abnormal strains being transmitted from the cloth to the burr wheel due to roughness and imperfections in the cloth.

2. In a tubular fabric knitting machine including a suitable bed, a rotating needle ring, and sets of knitting mechanism carried by the bed and stationary with respect to rotation of the needle ring, each set including a burr wheel located on the inner side of the needle ring with a portion of its periphery coacting with the needle ring and cloth adjacent the ring; of a shield enclosing the rear side of the burr wheel with respect to the direction of rotation of the needle ring and having a cut-out portion on the margin thereof adjacent the needle ring.

3. In a tubular fabric knitting machine including a suitable bed, a rotating needle ring, and sets of knitting mechanism carried by the bed and stationary with respect to rotation of the needle ring, each set including a burr wheel located on the inner side of the needle ring with a portion of its periphery coacting with the needle ring and cloth adjacent the ring; of a shield enclosing the rear side of the burr wheel with respect to the direction of rotation of the needle ring and having a cut-out portion on the margin thereof adjacent the needle ring, the shield being in the general form of a cup in which the burr wheel is nested.

4. In a tubular fabric knitting machine including a suitable bed, a rotating needle ring, and sets of knitting mechanism carried by the bed and stationary with respect to rotation of the needle ring, each set including a burr wheel lo-

cated on the inner side of the needle ring with a portion of its periphery coacting with the needle ring and cloth adjacent the ring; of a support for the burr wheel including a shank by means of which it is attached to the bed of the machine and formed with a cup in which said burr wheel is rotatably mounted, the cup being located on the rear side of the burr wheel with respect to the direction of rotation of the needle ring and enclosing the rear side and periphery of the burr wheel and having a cut-out portion adjacent the needle ring, all whereby the cup serves as a shield to relieve the burr wheel of abnormal strains on the cloth due to roughness and imperfections in the cloth tending to distort and disarrange the burr wheel.

5. In a tubular fabric knitting machine including a suitable bed, a rotating needle ring, and sets of knitting mechanism carried by the bed and stationary with respect to rotation of the needle ring, each set including a burr wheel located on the inner side of the needle ring with a portion of its periphery coacting with the needle ring and cloth adjacent the ring; of a support for the burr wheel including a shank by means of which it is attached to the bed of the machine and formed with a cup in which the burr wheel is rotatably mounted, the cup being located on the rear side of the burr wheel with respect to the direction of rotation of the needle ring and enclosing the rear side and periphery of the burr wheel and having a cut-out portion adjacent the needle ring, all whereby the cup serves as a shield to relieve the burr wheel of abnormal strains on the cloth due to roughness and imperfections in the cloth tending to distort and disarrange the burr wheel, said cup having an axial bore in the bottom thereof, a stud coaxial with the bore, and the burr wheel having a hub extending into the bore and rotatably mounted on the stud.

6. In a tubular fabric knitting machine including a suitable bed, a rotating needle ring, and sets of knitting mechanism carried by the bed and stationary with respect to rotation of the needle ring, each set including a burr wheel located on the inner side of the needle ring with a portion of its periphery coacting with the needle ring and cloth adjacent the ring; of an arcuate shield enclosing the peripheral edge of the rear side of the burr wheel with respect to the direction of rotation of the needle ring, the shield extending from a point adjacent the needle ring rearwardly at least partly around the burr wheel.

7. In a tubular fabric knitting machine including a suitable bed, a rotating needle ring, and sets of knitting mechanism carried by the bed and stationary with respect to rotation of the needle ring, each set including a burr wheel located on the inner side of the needle ring with a portion of its periphery coacting with the needle ring and cloth adjacent the ring; of an arcuate shield enclosing the peripheral edge of the rear side of the burr wheel with respect to the direction of rotation of the needle ring, the shield extending from a point adjacent the needle ring rearwardly at least partly around the burr wheel, a support for the burr wheel having a recess in which the hub of the burr wheel is mounted, the hub having a radially extending arm, and the shield being carried by said arm.
